VARIABLE CONDENSER

Filed June 10, 1924

FIG. 1

INVENTOR
WILLIAM DUBILIER

BY

William Dubilier
ATTORNEY

UNITED STATES PATENT OFFICE.

WILLIAM DUBILIER, OF NEW YORK, N. Y., ASSIGNOR TO DUBILIER CONDENSER CORPORATION, OF NEW YORK, N. Y., A CORPORATION OF DELAWARE.

VARIABLE CONDENSER.

Application filed June 10, 1924. Serial No. 719,116.

This invention relates to improvements in electrical condensers; especially electrical condensers so designed that the capacity thereof can be varied as desired, to suit practical conditions.

An object of this invention is to provide a variable electrical condenser which is simple in structure, which can be conveniently mounted upon a panel or other support, which 10 is easy to operate, and which is so constructed that, upon the parts being adjusted in a predetermined manner, the condenser will afford, with the greatest sharpness and accuracy, the precise measure of capacity required. 15 Other objects and advantages of this invention will appear from the following description, taken with the accompanying drawings, in which the preferred embodiment of my invention is illustrated. But this 20 disclosure is of course explanatory only, and I may make changes in the device actually shown without departing from the scope and spirit of this invention, to the full extent indicated by the broad and general meanings 25 of the terms in which the appended claims are expressed.

On the drawings, Figure 1 is a top plan of the exterior of the casing of a variable condenser according to my invention;

30 Figure 2 is a longitudinal section on the line 2—2 of Figure 1;

Figure 3 is a bottom plan of such a condenser;

35 Figure 4 is a plan view of a detail, showing the manner in which the conducting elements of the condenser are disposed in the required relation to each other; and

Figure 5 is a section taken on the line 5—5 of Figure 4.

40 The same characters on the drawings identify the same parts throughout.

Indicated by the numeral 1 is a casing of suitable size and shape of any convenient material. This casing is shown as being closed 45 at the sides, ends and top, but open at the bottom. On the inside of the casing is a pair of elements of conductive material 2, such as plates or sheets of thin metallic foil, and associated with these elements is a plate 50 or member 3, the plates 2 being disposed between this plate and the top 4 of the casing. The elements 2, the plate 3 and the other operative parts of the condenser, are situated in a chamber 5, enclosed by the casing 1; this 55 casing as the drawings illustrate, being ob-

long or rectangular, and of the height or depth required; while the chamber 5 and plate 3 therein are of corresponding shape.

On the top of the casing is an exterior circular protuberance 6 in central position and 60 passing through this protuberance is a bore 7, which is counterbored or enlarged at the protuberance 6 to form a conical seat 8. The bore 7 receives the reduced end 9 of a stem or shaft 10, having thereon a peripheral flange 65 or collar 11 which is conical, to fit the seat 8; and the top 4 of the casing also carries a central boss 12 projecting from the inner surface of the top down into the chamber 5 and terminating at its lower end in a conical seat 70 13; the bore 7 passing through the protuberance 6, and the boss 12, and being open at both ends.

As indicated in Figure 2, the plate 3 has a large threaded central opening 14 of greater 75 diameter than the boss 12, and when this plate is in position, the bore 7, the boss 12, and the threaded opening 14 in the plate will be in concentric relation. Into the threaded opening 14 is screwed a central externally 80 threaded head or nut 15, which has a threaded bore 16 therethrough of the same diameter as the bore 7 and adapted to align therewith. The face of the head 15, which is presented to the boss 12, is bored out concentric with the bore 16, as indicated at 17, and the bottom of the recess 17 is made conical, as indicated at 18, to fit the conical seat 13, at the inner end of the boss 12. To make connection between the stem or shaft 10, and the head 15, 85 I thread the extremity of the lower end 9 of this stem and screw it into the threaded bore 16 of the head 15. When the stem 10 is turned up to a sufficient extent, the threads of the extremity of the end 9 will draw the head 15 against the boss 12, and cause the conical collar 11 of the stem 10, and the conical surface 90 18 of the nut 15, to make firm contact with the conical seats 8 and 13; but without producing any interference to the rotation of the stem of the head 15, when the condenser is 95 to be operated. The inside of the bore 7 is of course smooth.

For the purpose of securing the stem 10 to the head 15 in rigid relation, I may employ a 100 binding screw 19, which enters the threaded bore 16 from below and engages the extremity of the threaded end 9. When the binding screw 19 is turned up tightly enough against the extremity of the end 9, it is capable of 110

causing the threads of the end 9 to engage so tightly with the threads in the bore 16, that when the stem 10 is turned, the head 15 will always turn with it in either direction, and no lost motion between the end 9 and the head 15 will occur. Over the outer end of the binding screw 19, I may screw a nut 20, and upon one face or end of this nut will rest a perforated washer 21. At 22 is indicated a spring in the form of a resilient plate of curved metal of substantially the same width as the plate 3; the upper face of this plate being concave and the lower face convex. The extremities of the spring plate 22, therefore, engage the lower side of the plate 3, and the middle of this spring will rest upon the washer 21. Of course, the plate 22 will be perforated to allow the screw 19 to pass through it. The middle portion of this spring plate will lie between the washer 21 and the lower end of the head 15, and the nut 20 will be turned up on the screw 19 just enough to cause the washer to press against the spring, but not enough to make this spring 25 plate or device 22 turn or revolve about the screw 19 as an axis, when the shaft 10 is rotated to turn the head 15 in the threaded opening 14 of the plate 3. When the nut 20 is screwed up just enough to grip the washer 30 21, and the plate 22 lightly, against the lower end of the head 15, the nut may be locked on the screw by any suitable means.

It will now be apparent that when the shaft 10 is turned, the end 9, the head 15, the binding screw 19 and the nut 20, will rotate together in unison, while the member 3 and plate 22 will not rotate, being held against rotation by the opposite lateral surfaces of the inside of the chamber 5. The turning of the head 15 in the threaded opening 14 of the plate 3 will serve to raise or lower this member, to vary the distance between it and the inside face of the top 4. When the plate 3 is lowered, the ends of the spring 22 will be 45 pressed down, and when the plate is raised, the ends of the spring 22, on account of the resiliency of the metal, rise with it. Hence, the ends of this spring always press up forcibly against the bottom of the plate 3, and thus 50 compensate for any looseness or wear upon the threads on the outside of the head 15, and the inside of the aperture 14; that is, the spring will always hold the top faces of the threads in the aperture 14 firmly against the 55 lower faces of the threads on the outside of the head 15.

The elements 2 are in the same plane and in longitudinal alinement, but have their adjacent ends separated, as indicated particularly in Figures 2, 4 and 5. I prefer to place these elements between covering sheets of mica 23 which are provided at the center with registering openings 24. These openings are of smaller diameter than the width of the 60 space between the adjacent ends of the ele-

ments 2, and the opposite ends of the elements 2 are allowed to project somewhat and are bent over upon the outside of one of the mica sheets, which are there engaged by pieces of metal bent centrally lengthwise, to make 70 clips 25 and grip the mica sheets and overturned ends of the plates 2 between them. With this construction, the two elements can be handled as a unit, and when placed between the member 3 and top 4, the boss 12 will pass 75 through the registering apertures 24. I also employ in the space between the plate 3 and top 4 of the casing, a pair of leaf springs in the form of curved metal plates similar to the spring plate 22 and indicated in Figure 2, by 80 the numerals 26 and 27. The spring 26 engages at its extremities against the under side of the top 4, and is perforated in the middle to enable the boss 12 to pass through it. The metal composing it is so set that the lower face 85 of this spring is concave and presses down upon the upper one of the mica sheets 23. Upon the other hand, the spring 27 is convex on its upper face, resting at its ends upon the top of the plate 3 and pressing up in the 90 middle against the lower mica sheet; both plates or springs 26 and 27 having central apertures like the aperture 24, to permit the boss 12 to pass through them.

The manner in which the condenser is operated to vary the capacity will now be clear. If each of the elements 2 is connected to the two extremities of an electrical circuit, the capacity of the condenser can be decreased by turning the shaft 10, upon which, in practice, a suitable knob will be affixed, so as to make the plate 3 move down and thus increase the distance between it and the top 4. The two springs 26 and 27 will then both become more convex on the faces which they present to the plates 2, that is, the ends of these two springs will move farther away from the elements 2. But if the shaft 10 is turned to make the head 15 lift the plate 3, the lower spring 26 is caused to become flatter and through its middle portion it acts to press upward upon the mica sheets 23, lifting the mica sheets and the elements 2 somewhat and flattening out, to some extent, the upper spring 26. The effect of this is to bring the ends of the two springs 105 26 and 27 closer to the elements 2 and thus bridge to a greater extent, the space between these two sheets. The capacity of the condenser is thereby increased, because the springs 26 and 27 also serve as condenser 110 plates, although they are not directly connected in circuit. They may be called "floating" or isolated plates.

The ends of the condenser have openings therein to receive insulating bushings 28, 12 against the outer extremities of which are insulating washers 29. Inside of the casing, against the adjacent extremities of the bushings 28, I place metallic washers 30, which are of such shape, that they have a straight edge 130

- on the top to engage the inside face of the top 4, and through the insulating bushings 28 and washers 29 and 30 are passed socket pieces 31, having threaded bores 32, open to the outside 5 of the casing; while the inner ends of these socket pieces carry heads 33 to fit against the washers 30, and these heads 33 are joined by conductors 34, one to each of the metal clips 25. Into the bores 32 of the sockets 31, are 10 inserted binding screws 35 to enable electrical conductors to be connected to the sockets 31, and on the outside of the casing and against the washers 29, I may place locking washers 36 encircling the exterior end of the sockets 15 31, the exterior ends of these sockets being expanded against the washers 36, so as to bind the heads 33, the washers 30, the bushings 28, the washers 29 and 36, and the socket pieces, firmly together.
- 20 The stem or shaft 10 may carry a projection 37 to engage with a stop 38 upon the protuberance 6, to limit the shaft 10 to one revolution, but obviously, I may so design the condenser to permit less than one revolution, 25 or more than a complete revolution of the shaft 10.
- The opposite ends of the casing 1 may have 30 projections 39 with threaded openings 40 to enable the condenser to be secured to a bench, table, wall or other support; and the top may have projections or bosses 41, with threaded 35 apertures 42 to enable the condenser to be secured to the inside of a panel; that is, upon the rear face, which will be apertured to permit the shaft 10 to pass through it, and have the knob affixed to this shaft located on the outer face or front of the panel.
- The open lower end of the casing may have 40 a shoulder 43 to receive a closure 44, which may be fastened in place by any well-known means. I may also provide the inside of the casing with vertical ribs 45, at each side of the chamber 5, to prevent any turning or twisting of the plates 3, or the springs 22, 26 and 27, or 45 of the mica sheets 23 holding the elements 2, and I may provide the washers 30 with projecting portions 46 to engage a straight edge or recess of the heads 33 upon the inner ends 50 of the sockets 31, so that when the screws 35 are tightened, these sockets will not turn in the bushings 28. A locking pin is indicated at 47 in Figure 3 to illustrate an example of the means employed to secure the nut 20 in the desired position upon the screw 19; but obviously, no locking pin is needed at this point 55 because after the screw 19 has been tightened, the nut 20 can be fastened thereon as required, by driving the point of a punch into the threads at the point 47.
- 60 From the foregoing description, it will be seen that the parts of the condenser are all correctly assembled and maintained in true position, so that when the stem 10 is rotated through any particular arc, the desired capacity will always result, because whenever the shaft 10 is turned to a pre-determined extent, the member 3 actuating the spring 27 and likewise the spring 26, will always occupy the same corresponding position, and so while the two springs are bridging the 70 space between the elements 2, no looseness can take place between the head 15 and the plate 3, because of the compensating effect of the spring 22. The precise capacity desired can thus always be secured, and the accuracy of the condenser maintained.
- 75 In the construction above described, the elements 2 together with the mica covering sheets 23, are limited in their movement within the smallest possible compass. While some 80 movement of the elements 2, and mica sheets 23 is unavoidable, this movement should be restricted to the utmost, because the mica is fragile and brittle, and any stress to which it may be subjected may produce cracks in the 85 mica which will expose the elements 2 more or less, and thus destroy or greatly impair the efficiency of the condenser.
- Hence, the conductors 34 must be made 90 light and flexible, so that when the condenser and the mica move up or down, the mica sheets are not caused to bend at the ends and thus no force whatever is applied to the mica, except the force of compression exerted at the middle by the opposed convex 95 faces of the springs 26 and 27. This force, however, is of such a character that it can do no damage to the mica in any of the positions which the mica and the metal sheets 2 may assume in the small range of movements 100 permitted to them. Of course the shape of the casing 1 need not necessarily be oblong, but may be varied as desired.
- 105 It is understood that in the foregoing disclosure, the bottom view of the condenser shown in Figure 3 omits the closure 44 for the sake of clearness.
- In Figure 2, the electrically conductive sheets 2, the mica plates 23 and the spring plates 26 and 27 are shown in edge or side 110 view, and not in section, for the sake of convenience and clearness.
- The structure of the condenser proper comprising the plates 2 and the cooperating parts 26 and 27, is not recited in the claims 115 of this application, but is set forth in the claims of my copending application, Serial No. 719,115, filed June 10th, 1924.
- Having described my invention, what I believe to be new and desire to secure and protect by Letters Patent of the United States is:
- 120 1. A variable electrical condenser including a casing, an operating member, a rotatable head in the casing engaging said member, 125 said head being held against movement along the axis of its rotation, and said member being held against rotatable movement, but being free to move bodily along said axis, and a compensating device engaging both said 130

head and said member to maintain said member and said head in precise engagement with each other.

2. A variable electrical condenser comprising electrically conductive elements in operative relation separated by dielectric material, a casing, a rotatable head in said casing, said casing carrying a boss against which the head is seated, an operating stem engaging the head and projecting through the casing to the outside for rotating the head, the stem having a collar on the outside of the casing to engage the casing so that the head may rotate without shifting along the axis of the stem, an operating member in the casing and having threaded engagement with the head, and a bow spring having its middle portion supported adjacent said head and its extremities bearing upon said member to hold said member and said head in precise engagement.

3. An electrical condenser comprising elements of electrically conductive material in alinement with each other, but having their adjacent ends separated, dielectric material between the elements, an operating member to cause bridging of said elements and thus vary the capacity of the condenser, a head to have rotary engagement with said member and enable the member to be moved bodily along the axis of rotation, and a compensating device to hold the head and the member in precise engagement with each other.

4. A condenser comprising elements of electrically conductive material in alinement with each other, but having their adjacent ends separated, dielectric material between the elements, a member to cause bridging of said elements and vary the capacity of the condenser, said member being free to have bodily movement, but held against rotation, and a rotatable head having threaded engagement with the member, said head being held against movement along the axis of rotation, and a compensating bow spring having its middle portion supported adjacent said head, and having its ends bearing against the member to maintain the head and the member in precise engagement.

5. A condenser comprising elements of electrically conductive material having their ends separated, dielectric material between the elements, a plate to bridge said elements and vary the capacity of the condenser, an operating member for said plate, a head having rotary engagement with said member, said head being held against movement along the axis of rotation; while said member is supported to be held against rotation, while being free for bodily movement, and a spring associated with said head and member to maintain them in precise engagement.

6. A condenser comprising elements of electrically conductive material having their

ends separated, dielectric material between the elements, a plate for bridging said ends to vary the capacity of the condenser, an operating member held against rotation, but mounted to be free for bodily movement, a head having threaded engagement with said member and mounted to be rotated but engaged to be held against movement along the axis of rotation, and a bow spring having its middle portion supported adjacent said head and its extremities bearing against said member to secure precise engagement of the head and member.

7. A condenser comprising electrically conductive elements with intervening dielectric material, a casing, a member adapted to cause the capacity of the condenser to be varied, a rotatable head in the casing having threaded engagement with the member, said head being held against shifting along its axis of rotation, and said member being allowed to have bodily movement but being held against rotation, and a compensating device engaging both said head and said member to maintain precise engagement of the head and member,

8. A condenser comprising electrically conductive elements separated by a dielectric, an operating member, a casing in which said member is enclosed, a rotatable head having threaded engagement with the member, a projection against which said head is seated, the stem for said head projecting through the casing to the outside thereof and having a collar to engage the outside of the casing and hold the head against said projection to prevent axial movement of the head, the member being mounted to have bodily movement, but held against rotation, and a bow spring having its middle portion supported adjacent the head and having its extremities bearing upon the member to hold the member and the head in precise engagement.

9. An electrical condenser including a casing, an operating member to cause variation of the capacity of the condenser, a head in the casing adapted to have rotary engagement with said member and enable the member to be moved bodily along the axis of rotation, and a compensating device mechanically engaging the head and member to hold the head and the member in precise engagement with each other.

10. A condenser comprising conductive elements separated by dielectric material, a member adapted to cause variation of the capacity of the condenser, said member being free to have bodily movement, but held against rotation, and a rotatable head having threaded engagement with the member, said head being held against movement along the axis of rotation, and a compensating bow spring having its middle portion supported adjacent said head, and having its ends bear-

ing against the member to maintain the head and the member in precise engagement.

11. A condenser comprising electrodes separated by insulation, an operating plate, 5 adapted to cause variation of the capacity of the condenser, a head having rotary engagement with said plate, said head being held against movement along the axis, while said plate is supported to be held against 10 rotation, while being free for bodily movement along said axis, and a spring engaging both said head and member to maintain them in precise engagement.

12. A condenser comprising conductive elements separated by a dielectric, an operating member for causing variation of the capacity of the condenser, said member being held against rotation, but mounted to be free for bodily movement, a head having threaded engagement with said member and mounted 15 to be rotated, but engaged to be held against movement along the axis of rotation, and a spring engaging both said head and said plate to secure precise engagement thereof.

In testimony whereof I affix my signature.
WILLIAM DUBILIER.
